GUARD RAIL

Arthur R. Schulze, Johnstown, Pa., assignor to
Carnegie-Illinois Steel Corporation, a corpora-
tion of New Jersey

Application July 2, 1947, Serial No. 758,600

3 Claims. (Cl. 238—17)

1

This invention relates to improvements in railroad track guard rails.

In railroad tracks particularly at frogs installed in switches and crossovers, and around trestles and curves, guard rails are mounted inside the running rails and provide means for engaging wheel flanges, thereby preventing train derailment. Guard rail faces which wheels engage are preferably of hard, wear-resistant material, such as manganese steel. Costs of such material are relatively high compared with soft, low carbon steel suitable for the rail supporting structure.

An object of the present invention is to provide guard rails wherein bearing surfaces are of hard, wear-resistant material and yet by improved design the quantity of such material needed is minimized.

Further objects of the invention are to provide improved preassembled guard rail units ready for installation in railroad track without alteration of the track structure; to provide improved guard rail mountings for transmitting lateral thrusts directly to running rails; to provide unitary guard rails which do not interfere with spiking of running rails to ties; and, in a modified form of the invention, to provide improved unitary guard rails and tie plates.

In accomplishing these and other objects of the present invention, I have provided improved structural details, preferred forms of which are shown in the accompanying drawings, wherein:

Figure 1 is a top plan view of a section of railroad track having installed thereon an improved guard rail embodying features of the present invention;

Figure 2 is a transverse vertical sectional view taken substantially on line II—II of Figure 1;

Figure 3 is a longitudinal vertical sectional view taken substantially on line III—III of Figure 1; and

Figure 4 is a transverse vertical sectional view similar to Figure 2, but showing a modified construction.

Referring more in detail to the drawings:

Figure 1 shows one running rail 10 and ties 11 of a conventional railroad track. The rail is secured to the ties by tie plates 12 and spikes 13, as well known in the art. A guard rail is mounted alongside the running rail for engagement by wheel flanges for preventing train derailment.

In accordance with the present invention, the guard rail and its mounting means are formed as a preassembled unit, designated 14. In the form of the invention shown in Figures 1 to 3,

such unit is adapted for installation in existing railroad track without alteration of the track.

As best shown in Figure 2, guard rail unit 14 comprises an elongated wearing rail 15, L-shaped securing brackets 16 and an angle iron assembly member 17, all permanently secured together as by welding.

Wearing rail 15 is an elongated bar extending parallel to running rail 10 at approximately the same height and spaced inwardly therefrom. At least the outer surface of the wearing rail adjacent the running rail is hardened and resistant to wear when engaged by wheel flanges. Such hardness may be obtained by any appropriate means known in the art, such as by use of hard alloy steels or by surface hardening.

A plurality of brackets 16 are secured to rail 15 and are positioned so that brackets may lie between the ties (Figures 1 and 3). There may be either one or more brackets in each space between two ties. The brackets are preferably of the configuration shown in Figure 2. Each bracket has an upright leg 18, the upper inner corner of which is recessed to receive rail 15, a horizontal leg 19, adapted to extend under rail 10 and engage the under face thereof, and a gauge stop 20 adapted to engage the outer side of rail 10 to position rail 15 with respect to rail 10 and transmit forces from the former to the latter. As the guard rail wears, it may be positioned closer to the running rail by insertion of shims between gauge stop 20 and the running rail.

Angle iron assembly member 17 has an upwardly extending leg 21 affixed to the outer edges of upper right bracket legs 18 and a horizontal leg 22, apertured as at 23 to be spiked to the tie. The assembly member transmits overturning forces applied to the guard rail to the ties.

In accordance with usual practice, foot guards are mounted between the ends of the guard rail and the running rail for preventing workers' feet from being trapped between the rails. Said foot guard includes a plate 24, welded or otherwise secured to the lower face of rail 15 and extending to the proximity of the running rail.

Opposite ends of the guard rail may be bent down, as indicated at 25, and plate 24 follows the contour of the bent portion. End brackets 26 are preferably welded to the ends of the guard rail, and are similar to brackets 16, except for their reduced height.

A guard rail unit constructed as described may be installed on existing railroad track merely by placing horizontal bracket legs 19 beneath the running rail between ties and hooking gauge stops

28 over the base flange of said rail. The unit may then be fixed in place by spikes 27 driven through apertures 28 in assembly member 17. It is seen that such installation does not necessitate altering or disturbing existing track in any way.

Thrusts applied to the guard rail are transmitted directly to the running rail through brackets 18 and particularly horizontal legs 19 and gauge stops 20 thereof.

In the modified assembly shown in Figure 4 the tie plates are integrated with the guard rail unit, but otherwise the structure is similar.

The assembly of Figure 4 comprises a wearing rail 30, brackets 31 and an angle iron assembly member 32, affixed together as in the construction just described. Tie plates 33 are affixed between adjacent pairs of brackets 31 as by welding, and thus constitute part of the unit. Due to this feature, it is unnecessary that the horizontal bracket legs extend to the outside of the rail, but they may terminate beneath the rail as shown. The integrated tie plates and the assembly member are spiked to the ties, the tie plate performing its usual function of fixing the running rail on the tie.

Shims 34 may be interposed between brackets 31 and the inner base flange of the running rail for properly positioning the guard rail.

The modified unit has particular application for new track construction. It has the advantage of providing guard rails and tie plates already assembled in a preformed unit, and thus decreases the number of separate parts that must be available.

In both forms of units the brackets and assembly members may be of soft, low carbon steel, since they are not subject to wear. Only the wearing rail or the bearing surface thereof need be of more costly wear-resistant material; thus the material cost of the unit may be kept at a minimum.

While I have shown only certain embodiments of the invention, it is apparent that the structure is subject to further modification without departing from the spirit of the invention. Therefore I do not wish to be limited by the disclosure set forth, but only by the scope of the appended claims.

I claim:

1. A preassembled railroad track guard rail unit comprising an elongated wear-resistant steel rail of substantially rectangular cross section, a plurality of spaced L-shaped brackets of softer low-carbon steel having horizontal and upright legs, the upper inner corners of said upright legs being recessed and receiving and supporting said rail and being welded thereto, said horizontal legs being adapted to extend beneath a running rail in the spaces between ties, gauge stops on the upper extremities of said horizontal legs for hooking over the flange of the running rail and positioning said first named rail, and an angle iron

assembly member welded to the outer edges of said upright legs and adapted to be spiked to ties.

5 2. A preassembled railroad track guard rail unit for installation on existing railroad track without disturbing the latter comprising an elongated wear-resistant steel rail of substantially rectangular cross section, a plurality of spaced L-shaped brackets of softer low-carbon steel having horizontal and upright legs, the upper inner corners of said upright legs having recesses of configuration similar to the cross-section of said rail and receiving and supporting said rail and being welded thereto, said horizontal legs being adapted to extend beneath a running rail in the spaces between ties, gauge stops on the upper extremities of said horizontal legs for hooking over the flange of the running rail and positioning said first named rail inwardly of the running rail and in spaced relation above the ties, and an elongated angle iron assembly member welded to the outer edges of said upright legs and adapted to be spiked to ties.

10 3. A preassembled railroad track guard rail unit for installation on existing railroad track without disturbing the latter comprising an elongated wear-resistant steel rail of substantially rectangular cross section, a plurality of L-shaped brackets of softer low carbon steel spaced along the length of said rail and having horizontal and upright legs, the upper inner corners of said upright legs being recessed and receiving and supporting said rail and being welded thereto, said horizontal legs being adapted to extend beneath a running rail in the spaces between ties, gauge 15 stops on the upper extremities of said horizontal legs for hooking over the flange of the running rail and positioning said first named rail inwardly of the running rail and in spaced relation above the ties, and an elongated angle iron assembly member welded to the outer edges of said upright legs and adapted to be spiked to ties.

20 4. A preassembled railroad track guard rail unit for installation on existing railroad track without disturbing the latter comprising an elongated wear-resistant steel rail of substantially rectangular cross section, a plurality of L-shaped brackets of softer low carbon steel spaced along the length of said rail and having horizontal and upright legs, the upper inner corners of said upright legs being recessed and receiving and supporting said rail and being welded thereto, said horizontal legs being adapted to extend beneath a running rail in the spaces between ties, gauge 25 stops on the upper extremities of said horizontal legs for hooking over the flange of the running rail and positioning said first named rail inwardly of the running rail and in spaced relation above the ties, and an elongated angle iron assembly member welded to the outer edges of said upright legs and adapted to be spiked to ties.

30 5. A preassembled railroad track guard rail unit for installation on existing railroad track without disturbing the latter comprising an elongated wear-resistant steel rail of substantially rectangular cross section, a plurality of L-shaped brackets of softer low carbon steel spaced along the length of said rail and having horizontal and upright legs, the upper inner corners of said upright legs being recessed and receiving and supporting said rail and being welded thereto, said horizontal legs being adapted to extend beneath a running rail in the spaces between ties, gauge 35 stops on the upper extremities of said horizontal legs for hooking over the flange of the running rail and positioning said first named rail inwardly of the running rail and in spaced relation above the ties, and an elongated angle iron assembly member welded to the outer edges of said upright legs and adapted to be spiked to ties.

40 6. A preassembled railroad track guard rail unit for installation on existing railroad track without disturbing the latter comprising an elongated wear-resistant steel rail of substantially rectangular cross section, a plurality of L-shaped brackets of softer low carbon steel spaced along the length of said rail and having horizontal and upright legs, the upper inner corners of said upright legs being recessed and receiving and supporting said rail and being welded thereto, said horizontal legs being adapted to extend beneath a running rail in the spaces between ties, gauge 45 stops on the upper extremities of said horizontal legs for hooking over the flange of the running rail and positioning said first named rail inwardly of the running rail and in spaced relation above the ties, and an elongated angle iron assembly member welded to the outer edges of said upright legs and adapted to be spiked to ties, the extremities of said first named rail being bent downwardly, L-shaped brackets at the extremities of said first named rail similar to said first named brackets but of reduced height, and foot guard plates welded to said angle iron between the last pairs of brackets.
